UNITED STATES PATENT OFFICE

JAN BLOKLAND VISSER, OF FLUSHING, NETHERLANDS, ASSIGNOR TO NAAMLOOZE VENNOOTSCHAP: KONINKLIJKE MAATSCHAPPIJ "DE SCHELDE", SCHEEPSBOUW EN WERKTUIGENFABRIEK, OF FLUSHING, NETHERLANDS, A CORPORATION OF THE NETHERLANDS

PASSENGER SHIP

Application filed October 24, 1931, Serial No. 570,944, and in the Netherlands November 1, 1930.

The invention relates to a passenger ship or cargo- and passenger ship with outer and inner cabins arranged athwartships with regard to each other.

5 If the inner cabins in athwartships direction are situated completely behind the outer cabins, as is the case in many passenger ships and cargo- and passenger-ships these inner cabins have no direct communication with the open air and moreover no daylight. Especially for ships travelling on tropic seas 10 this is a considerable disadvantage, the inner cabins of course being very undesirable owing to the absence of natural ventilation and the lack of daylight.

It has been tried in various ways to remove this drawback. Ships have been constructed in which, maintaining the total number, all 15 cabins have been made outer cabins by making the cabins in fore and aft direction narrower and in athwartships direction longer. However, by doing so the cabins obtain a 20 very unfavourable lengthened form.

In some passenger ships each inner cabin 25 ends in a narrow space, passing along the adjacent outer cabin which space communicates with the open air. This construction will not lead to an efficient natural ventilation and lighting, and moreover this space is generally 30 too narrow as to be included in the inhabitable part of the cabin.

The invention gives a definite solution of the given problem.

According to the invention one or more 35 rows of inner cabins are elevated in such a way that these inner cabins have a direct communication with the open air and the daylight across the relative outer cabins and in this way also obtain the character of outer 40 cabins.

The construction according to the invention will lead furthermore to a number of other important advantages.

In the first place the invention enables to 45 use the passages in fore and aft direction, which become available in consequence of the mentioned raising, for arranging the life-boats, for promenade deck or for service purposes.

50 Moreover the large number of outer doors

in the longitudinal walls of the passenger-deckhouse offers especially for service in the Tropics the advantage that the superstructure in which the passengers are accommodated, has the possibility of continuously 55 maintaining air currents.

By arranging the life-boats in the above mentioned passages they are placed on a lower level than on the boat deck used until now, so that they may be lowered with more 60 speed and safety. Their more central arrangement in the ship makes them more easily accessible for embarking.

Furthermore the centre of gravity of the life-boats will be situated lower, so that more 65 cabins may be arranged in the upper part of the ship, e. g. on the boat deck which will in that case become vacant. The space available for sport on this deck may be extended over the full width of the ship.

Finally according to the invention a part 70 of the space confined by the lower walls of the displaced inner cabins and the inner walls of the longitudinal passage of the outer cabins may be used as a trunk for various 75 pipings (pipes for water supply and draining purposes, ventilation duct electric mains, etc.).

By this a large number of valve-boxes in the ship's hull may be saved.

The elevated cabins and any cabins constructed above the same may be provided with windows instead of with side lights, due to the protected situation which also renders it possible to keep these windows open in almost every weather condition. Moreover the sunlight will not shine into the cabin too 85 violently, and therefore not cause any inconvenience which is a special advantage in the Tropics.

Moreover a natural consequence of the elevating of the inner cabins is that the dining rooms over a large part of their width may be built considerably higher than hitherto has been the case.

In the annexed drawing showing an embodiment of the invention by way of example, the figure is a cross section of a ship on which the cabins are arranged according to the invention.

Part 1 is an outer cabin belonging to a row of these cabs in fore and aft direction and 5 2 an inner cabin, also belonging to a row in the same direction. The cabins 2 are raised in such a way with regard to the cabins 1 with 10 their adjoining longitudinal passage 11, that they have direct communication with the open air. In the outer wall 3 of these cabins 2 one or more windows 4 are arranged, communicating with the longitudinal passage 5.

In the embodiment of the drawing a further row of cabins 10 is built upon the row of cabins 2, the windows 14 also communicating with the passage 5. The row of cabins 15 1 is accessible through the passage 11, and the cabins 2 and 10 by means of the passages 12 and 13.

The passage 5 in fore and aft direction is used for stowing the life boats 7. In this 20 embodiment they are stowed on a special part 6 of the deck, dividing the passage 5 into two parts arranged one above the other. The part 6 of the deck is made somewhat lower with regard to the deck C in order to prevent 25 looking into the cabins 10.

The row of cabins 2 being raised with regard to the row of cabins 1, a space is formed, confined by the inner wall of the passage along the cabins 1 and the floor of the cabins 30 2. This space may be used as a trunk 8, in which the pipings for water supply and draining purposes, the ventilating ducts and electric mains are fitted. If desired this trunk may contain any other pipings which 35 must be led along some distance in fore and aft direction through the ship.

Numeral 15 indicates the load-line, the 40 various decks being indicated by the letters A—K. The A-deck and the B-deck are available for promenade deck, sporting deck, state-rooms, special cabins etc.

The shape of the dining room 9 is much more favourable than in many of the constructions hitherto known because it is higher 45 for a considerable part of its width.

Within the limits of the invention, that is raising a row of inner cabins, various embodiments are possible.

I claim:—

50 1. A passenger ship or cargo- and passenger ship with outer and inner cabins arranged athwartships with regard to each other one or more rows of inner cabins being raised in their entirety by about one half of the height 55 of the cabin above the outer cabins so that the inner cabins have direct communication with the open air and the daylight across the relative outer cabins and in this way also obtain the character of outer cabins.

60 2. A passenger ship or cargo- and passenger ship according to claim 1, comprising a passageway for the outer cabins positioned between the outer and inner rows of cabins, extending in a fore and aft direction, and a 65 trunk for conduits defined by the floor of

the raised cabins and the inner side walls of said passageway.

3. A ship comprising a plurality of decks, one deck having outer and inner rows of 70 cabins, the superadjacent deck having its outer cabins positioned directly over said inner row of cabins and spaced above the superadjacent deck, said inner row of cabins being also spaced above the superadjacent deck a distance sufficient to place the same in direct 75 communication with the exterior atmosphere.

4. A ship comprising a plurality of decks, one deck having outer and inner rows of 80 cabins, the superadjacent deck having its outer 85 cabins positioned directly over said inner row of cabins and spaced above the superadjacent deck, said inner row of cabins being also spaced above the superadjacent deck a distance sufficient to place the same in direct communication with the exterior atmosphere, and an open deck positioned above the superadjacent deck at a level approximating the ceiling level of the raised inner row of cabins.

5. A ship with outer and inner cabins arranged athwartships with regard to each other, the inner cabins being at a level above the outer cabins equivalent to about one half the height of the cabins so as to afford communication of the inner cabins with the exterior atmosphere.

In testimony whereof I affix my signature.
JAN BLOKLAND VISSER.
